P. B. WALLACE AND F. H. FOX.

WORK HOLDER.

APPLICATION FILED FEB. 5, 1919.

1,326,999.

Patented Jan. 6, 1920.

UNITED STATES PATENT OFFICE.

PHILIP B. WALLACE, OF BURLINGAME, AND FRANK H. FOX, OF SAN FRANCISCO,
CALIFORNIA.

WORK-HOLDER.

1,326,999.

Specification of Letters Patent. Patented Jan. 6, 1920.

Application filed February 5, 1919. Serial No. 275,167.

To all whom it may concern:

Be it known that we, PHILIP B. WALLACE and FRANK H. Fox, citizens of the United States, residing, respectively, at Burlingame, 5 in the county of San Mateo, and in the city and county of San Francisco and State of California, have invented certain new and useful Improvements in Work-Holders, of which the following is a specification.

10 This invention seeks to provide a simple and efficient device which may be used wherever it is desired to firmly hold material upon which work is being done and is designed more particularly for use upon metal-bending machines of the type disclosed in Letters-Patent No. 1,206,742 and No. 1,206,743, granted November 28, 1916, and No. 15 1,263,301, granted April 16, 1918, to John S. Wheeler.

20 With the above and other objects in view, the invention consists in the novel construction, combination and arrangement of parts illustrated in the appended drawings and hereinafter described and claimed.

25 In the drawings—

Figure 1 is a side elevation of the complete device, holding for example, a pipe or tubing;

Fig. 2 is a longitudinal section;

30 Fig. 3 is a cross-section on line 3—3, Fig. 2;

Fig. 4 is a plan view with the handle removed, and illustrating the dog swung out as per dotted form to allow work-holder to 35 be adjusted to or from the work;

Fig. 5 shows an extra jaw for holding heated work;

Fig. 6 is a plan view of the arrangement shown in Fig. 5;

40 Fig. 7 is a perspective view of the chain holding hook.

Numeral 1 indicates a frame having slots 2 to suit, and upon the top portion 3 of which is mounted a bearing block 4. This 45 frame may be a portion of the frame of the bending machine. Studs 5 are arranged in the base or cross portion 6 of the block 4 and have a smooth finished portion 7 to slide within the slot 2, and below the slot a plate 8 is held by castellated nuts 9 and 10, and 50 cotter pins 11 on said studs. It is to be understood that one or more studs may be used or a lug on the block 4 fitting within the slot 2 may provide a guide for the block. A 55 link 12 is pivoted at 13 in a recess 14 in the

front end of the block 4 and forms the terminal of a chain 15, which extends over the work, for example, a pipe 16, seated in a jaw 17 having a lug portion 18 secured within the walled portion of the block 4 by a pin 60 or eye bolt 19, projecting side portions 20 and 21 of the jaw bearing against the front edges of the side walls 22 and 23 of the block. The chain 15 rides over a bearing consisting of rollers 24 interposed between 65 an outer ring 25, having an external annular groove 26, and an inner eccentric 27, having an external annular groove 28, for retaining rollers 24 in place. The eccentric 27 is provided with end shaft portions 29 and 30 70 which are rotatable in the slots 31 and 32 of the side walls 22 and 23. A suitable stem 33, preferably angular, is provided to receive a handle 34 for turning the eccentric. The chain 15 consists of a suitable number 75 of links to allow for any desired work in hand, the adjustment of the chain being effected by a yoke 36 having hooks 37 and 38 engaging one of the extended pivot pins 39 of the chain. The threaded stem 40 of the 80 yoke extends through a lug 41 of the block 4 and is held by a nut 42, a set screw 43 retaining the stem in place by bearing upon the intermediate body portion 44 of the yoke. The block 4 is slidable upon the frame 1 85 and we provide a holding and locking arrangement which is adjustable for any suitable work, and quickly releases the work-holder from its work. This arrangement consists of an anchor member 50 with a stud 90 51 arranged therein and extending through the slot 2 and a plate 52, a nut 53 upon the stud and bearing against said plate securing the member in place. A dog 54 is pivoted to the member 50 by a pin or stud 55, having a collar portion 56 seated in the member 50 and a reduced portion 57 seated in the dog. A cap screw 58 holds a washer 59 over the pin 55 and the dog to prevent rising of the dog, and a nut 60, co-operating with 100 the plate 52, holds the pin in place. It is to be noted that a curved edge portion 61 of the dog 54, concentric with the stud 55, engages a mating surface on the projecting ends 62 and 63 of bearing block 4 thereby 105 permitting the dog to swing laterally. It is to be understood that other suitable means may be adopted to accomplish a firm holding arrangement. In Figs. 5 and 6, a modified arrangement for holding a heated pipe 110

or other material is shown which employs an extra jaw member 70 having an opening 71 therethrough for the chain 15. An extended lip 72 bearing against the side of the block 4 prevents the jaw from moving out of alinement, when the pipe 73 or other material is being bent.

In operation, the work, for example a pipe 16, is clamped to the jaw 17, by 10 gaging a pin 39 in the hooks 37 and 38 of the yoke 36, which is adjusted in the lug 41 to suit. The eccentric 27 is to be below the center of the bearings 29 and 30 when the chain is secured over the work, as indicated 15 in dotted lines, Fig. 1, and the handle 34 is turned from the dotted to the full position as shown, whereby the eccentric locks itself over the center of pull between the work and lug 41, the end of the handle bearing upon 20 the frame. It is to be noted that the desired clamping effect may be accomplished by adjusting the lock nut 42 upon the yoke 36. It is to be understood that the eccentric, together with other parts may be altered with 25 in the scope of the claims.

Having thus described our invention what we claim as new and desire to secure by Letters-Patent of the United States, is as follows:

- 30 1. A clamping device comprising a bearing block having wall and connecting portions; a lug on the block; slotted portions in said wall portions; a jaw secured onto and within said wall portions; an eccentric anti-frictional roller rotatable in said slotted portions and between said wall portions; an adjustable yoke secured in said lug; a chain pivoted on the opposite end of bearing block 35 from said lug; said chain extending over said eccentric roller; said chain adaptable to be held by said yoke in lug, during the clamping of the chain upon work held in jaw by the rotation of said eccentric roller until locked over its center line of pull.
- 45 2. A clamping device comprising a bearing block having wall and connecting portions; a lug on one end of said connecting portion; a jaw at the opposite end thereof, secured onto and within said walled portions; slotted bearing portions in said wall portions; an eccentric anti-frictional roller rotatably mounted in said slotted portions; an adjustable yoke secured into said lug; said roller being above the plane of the yoke and lug; adjustable studs arranged in bearing block; said studs adaptable to secure or slide said bearing block upon a suitable frame; means to hold said bearing block in an adjusted position; a chain secured to portion of bearing block adjacent said jaw, and extending over said jaw and said roller and secured onto said yoke.
- 60 3. A clamping device comprising a slide-able bearing block; a lug on one end thereof; a jaw secured onto other end portion; an

eccentric roller mounted in suitable bearings above the plane of said lug and jaw; an adjustable yoke extending through said lug; a chain pivoted to the bearing block adjacent the jaw, and extending over the 70 jaw and said roller and secured upon said adjustable yoke; means to secure said bearing block in an adjusted position upon said frame, and means to rotate said roller.

4. A clamping device comprising a bearing block slideable upon a frame; a chain pivoted to one end thereof; a jaw secured therewith; an eccentric roller mounted onto said bearing block; said chain extending over said jaw with work therein, and the eccentric roller, an adjustable yoke secured to a suitable support upon the bearing block and having hooked ends to engage the chain; means to hold said bearing block in a set position, and means to rotate said eccentric 85 roller to secure the work in said jaw.

5. A clamping device comprising a block adjustable upon a suitable frame; a chain pivoted at one end thereof; a jaw secured onto said block; an eccentric roller mounted 90 onto said block; an adjustable hook secured onto other end of said block; a mating jaw with an opening therein; said chain extending from its pivoted point, through said opening of the mating jaw over said eccentric roller to said adjustable hook; means to rotate said roller and means to adjust said hook to clamp and hold material disposed between the jaws.

6. A clamping device comprising a fixed 100 support, a block suitably mounted thereon, means for securing the block in a set position, an eccentric mounted in the upper portion of the block, a jaw secured upon one end of the block, a chain attached to the block adjacent said jaw and above the fixed support and passing over work seated in the jaw and over the eccentric, an adjusting device secured on the block and engaging the free portion of the chain, and an anchor device secured upon the fixed support and bearing against the block.

7. A clamping device comprising a fixed support, a block slidably mounted thereon, means for securing the block in a set position, an eccentric in the upper portion of the block, a chain attached at one end to the block and passing over the eccentric to hold work between its point of attachment and the eccentric, an adjusting device on the block engaging the free portion of the chain, an anchor adjustably secured on the fixed support, and a dog pivotally mounted on the anchor and arranged to bear against the block.

In testimony whereof we affix our signatures.

PHILIP B. WALLACE. [L.S.]
FRANK H. FOX. [L.S.]
